UNITED STATES PATENT OFFICE.

ISRAEL LUDLOW, OF NEW YORK, N. Y.

SHELL-PACKING.

1,302,392.

Specification of Letters Patent. Patented Apr. 29, 1919.

Application filed July 29, 1918. Serial No. 247,338.

To all whom it may concern:

Be it known that I, ISRAEL LUDLOW, a citizen of the United States, and a resident of the city of New York, borough of Manhattan, in the county and State of New York, have invented a new and Improved Shell-Pack, of which the following is a full, clear, and exact description.

Among the principal objects which the present invention has in view are: to protect the rifling band of ordnance shells; to adapt packings for use on shells of several different sizes; to facilitate the exposure of the bands; and to adopt packing devices which may be used a number of times.

Drawings.

Figure 1 is a perspective view in outline of an ordnance shell showing the rifling band thereof and in conjunction therewith a packing constructed and arranged in accordance with the present invention;

Fig. 2 is a view of the packing on an enlarged scale, spread out and looking at the inner surface thereof;

Fig. 3 is a cross section of the packing, the section being taken as on the line 3-3 in Fig. 2.

Description.

As seen in the drawings, the packing is made from a continuous strip of material, the material employed being preferably sheet fiber. One edge 8 is folded back upon the body of the strip to form a double thickness. A shoulder 9 is thus formed which engages in service the forward edge 10 of the rifling band 11 with which a shell such as indicated by the numeral 12, is provided. The material 13 at the opposite edge of the packing is folded around a relatively narrow and thicker fiber strip 14. The strip 14 is equal to or greater than the projection of the band 11, and in service engages the edge 15. The combined thickness of the strip 14 and the material 13 is slightly greater than the projection of the band 11, and therefore effectively protects said band from damage by concussion or abrasion. The distance between the shoulder 9 of the edge 8 and the adjacent edge of the material surrounding the strip 14, is approximately the width of the rifling band 11. The portion 16 thus formed rests above to protect the upper surface of the band 11. The opposite ends of the packing have a series of

lacing holes 17 through which a suitable lace 18 is threaded as shown best in Fig. 1 of the drawings.

When provided with a packing such as described, the same is applied to the band 11 by being disposed thereupon. The lace 18 is threaded through the holes 17 and drawn tight and tied as shown in Fig. 1.

When the shell has arrived at its destination and it is desired to remove the packing, this is accomplished by untying the lace 18, to permit the packing to expand sufficiently to draw the same from over the band 11. The packing thus removed instead of being thrown on the waste heap, as formerly, may now be reserved and reshipped to the point of original shipment to be reused.

Claims.

1. A shell packing having a protecting split ring for surrounding the body of said shell adjacent the rifle band thereof, said ring extending in service beyond the exposed surface of said band for protecting said band; and a covering member extending in service over said band between the edges thereof, the edge portion of said member completely infolding said ring, the outer layer of said covering member binding the edge portion thereof between said ring and said outer layer for holding said ring in fixed relation to said covering member.

2. A shell packing having a protecting split ring for surrounding the body of said shell adjacent the rifle band thereof, said ring extending in service beyond the exposed surface of said band for protecting said band; a covering member extending in service over said band between the edges thereof, the edge portion of said member completely infolding said ring; and means embodying a lacing member and eyelets formed in said covering member for holding the edges of said covering member and said ring in service relation.

3. A shell packing having a protecting ring for surrounding the body of said shell adjacent the rifle band thereof, said ring extending in service beyond the exposed surface of said band for protecting said band; a covering member extending in service over said band between the edges thereof, the edge portion of said member completely infolding said ring; means embodying a lacing member and eyelets formed in said covering member for holding the edges of said covering

member and said ring in service relation; and means coöperating with said ring for holding said covering member in service relation to said band, said means embodying 5 a folded portion of said covering member, said portion being adjacent the edge of said covering member opposite that infolding said ring.

4. A shell packing having a protecting 10 split ring constructed of a fiber strip substantially rectangular in cross section for surrounding the body of said shell adjacent

the rifle band thereof, said ring extending in service beyond the exposed surface of said band for protecting said band; and a covering member extending in service over said band between the edges thereof, the edge portion of said member completely infolding said ring, the outer layer of said covering member binding the edge portion thereof 20 between said ring and said outer layer for holding said ring in fixed relation to said covering member.

ISRAEL LUDLOW.
